United States Patent Office

Des. 185,587
Patented June 23, 1959

185,587

BALLOON INFLATOR

Albert Van Dam, New York, N.Y., assignor to The Van Dam Rubber Co., Inc., New York, N.Y., a corporation of New York

Application December 26, 1958, Serial No. 53,913

Term of patent 14 years

(Cl. D34—15)

FIG. 1

FIG. 2

FIG. 3

Fig. 1 is a front elevational view of a balloon inflator showing my new design;

Fig. 2 is a side view thereof; and
Fig. 3 is a top plan view thereof.

I claim:

The ornamental design for a balloon inflator, substantially as shown.
